RADIO-FREQUENCY TRANSFORMER

Clayton W. Ramsden, Elizabeth, N. J., assignor to
 Bell Telephone Laboratories, Incorporated, New
 York, N. Y., a corporation of New York

Application April 16, 1945, Serial No. 588,682

5 Claims. (Cl. 171—119)

1

This invention relates to inductance devices particularly of the transformer type comprising inductively related primary and secondary windings.

An object of the invention is to provide means for adjusting the mutual inductance of two inductively related windings without changing the terminal connections for the windings.

A further object is to provide for the variation of the mutual inductance of two windings by an amount less than that which would be produced by the addition or removal of a complete turn of one of the windings.

In accordance with the preferred embodiment of the invention, the primary winding comprises two spaced coils serially connected in opposing relation and the secondary winding also comprises two spaced coils connected in opposing relation, each of the secondary coils surrounding one of the primary coils. With such an arrangement small changes in the mutual inductance of the windings may be readily produced by varying the position of the connecting means between the adjacent turns of the two coils of the outer winding. For example, portions of the adjacent turns of the two coils of the outer winding may comprise parallel conductors of substantial cross-sectional area and a cross-strap between said portions before permanent connection thereto may be adjusted to a position giving the desired mutual inductance. Such a mutual inductance adjustment is particularly advantageous since the mutual inductance may be varied without changing the terminal connections of the windings and thus permits a definite location of the circuit wiring for the device.

Referring to the drawings:

Fig. 1 is a side elevation of an inductive device embodying the invention;

Fig. 2 is another view of the device of Fig. 1 with the outer winding and the end portions broken away;

Fig. 3 is an end view partly in section of the device of Fig. 1 taken in the direction indicated by the arrows 3—3 of Fig. 1;

Fig. 4 is a schematic view of the winding arrangement of Fig. 1 illustrating the direction of the flux produced by the inner winding; and

Fig. 5 is a circuit diagram of the windings of Fig. 1.

Referring more particularly to Figs. 1 and 2, the transformer disclosed therein comprises a hollow cylinder or tube 10 of insulating material surrounded by a two-section primary winding and a two-section secondary winding. One sec- 55

2

tion of the primary winding comprises a ribbon-shaped conductor 11 spirally wound around tube 10 and extending between the terminal 12 and a metal strap 13 to which a mid-point terminal 14 is connected; the other section of the primary winding comprises a spirally wound ribbon-shaped conductor 15 extending between the metal strap 13 and the outer terminal 16. The two conductors 11 and 15 are wound around the tube 10 and so connected as to produce opposing fluxes; and they may comprise the same number of turns so that terminal 14 provides a mid-point connection.

A second insulating tube 17 surrounds the central portion of tube 10 and serves as a support for the secondary winding. If desired, the internal diameter of tube 17 may be somewhat greater than the external diameter of tube 10 in which case any suitable means may be provided for supporting tube 17 with its axis coinciding with the axis of tube 10. One section of the secondary winding mounted on tube 17 comprises a single turn of a ribbon-shaped conductor 20 while the other section comprises a single turn of a ribbon-shaped conductor 21. As shown in Figs. 1 and 3, the two ends of each of the turns 20 and 21 are spaced apart slightly. One way in which the ends of the turns 20 and 21 may be fastened or terminated is shown in Fig. 3. Suitably mounted on tube 17 is an insulating strip 22 having two slots 23 and 24, one for each turn. One end 25 of turn 21 passes under strip 22 up through slot 24 and then bent back on itself. The other end 26 of turn 21 after passing underneath strip 22 and upwardly through slot 24 is suitably formed to provide a terminal portion 27. The ends of turn 20 are similarly formed around the slot 23 in strip 22 with one end of turn 20 being provided with a terminal 28. The ends of the turns 20 and 21 remote from terminals 27 and 28 are interconnected by a cross-strap 31 which may be adjusted to any desired position either close to slots 23, 24 or remote therefrom.

Schematic views of the windings are shown in Figs. 4 and 5. As previously described, the two primary winding sections 11 and 15 are connected in series opposition so that the direction of the flux linking the primary and secondary windings may be represented by the two arrows 32, 33 of Fig. 4. But since the two sections 20 and 21 of the secondary winding are also connected in series opposition, it follows that the currents induced in the secondary winding sections 20 and 21 will be in aiding relation. The above coil construction has special advan-

ages when extremely close inductance requirements must be met in the primary winding since the mutual inductance of the two windings may be readily adjusted to a desired value without changing the position of the terminals 12, 14, 18, 22 and 28 which are used for including the transformer in an electrical circuit. In making such an adjustment it is generally preferable to first adjust the self-inductance of the primary winding 11, 15 to the desired value, for example, by varying the positions within the winding sections of two cores 35 and 36 made either of copper or a suitable magnetic material. These two cores 35, 36 are mounted on the ends of threaded rods 37 and 38 of non-magnetic material, such as brass, which are threaded through end pieces in tube 10 with their external ends being provided with knobs 39 and 40 whereby the rotation of rods 37, 38 will produce longitudinal movements of cores 35 and 36 along the axis of the core tube 10. When these cores 35, 36 have been adjusted to provide the desired self-inductance for primary winding 11, 15 then the coupling between the primary and secondary windings may be adjusted by varying the location of the cross-strap 31 which connects turn 20 to turn 21. If the mutual inductance is less than the desired value when cross-strap 31 is in the position shown in Fig. 1, the mutual inductance may be increased by moving strap 31 closer to ends 25, 30 of the turns 20, 21; while if the position of strap 31 in Fig. 1 gives too large a mutual inductance, then the mutual inductance may be reduced by moving strap 31 farther away from the end portions 25, 30. When the desired location of strap 31 has been determined it may be fastened, for example by soldering, to the winding turns 20 and 21. In making such an adjustment it is preferable that the connected points on turns 20, 21 should be equidistant from the end portions 25, 30 so that the utilized fractional portion of turn 20 will exactly equal the utilized fractional portion of turn 21. Strap 31 should also preferably lie parallel to the axis of tube 10.

In the particular embodiment shown, each of the secondary winding sections consists of a single turn but obviously the invention may be applied to constructions where the inductive requirements are such as to require more than one turn in each secondary winding section. The inductive device of Fig. 1 may be supported in any suitable manner as, for example, by means of studs 42.

It will be understood that this invention is not limited to the specific construction herein illustrated and that the various features of the invention may take various other forms within the scope of the appended claims.

The inductance device of this invention possesses particular advantages for use in the high frequency field, for example, for frequencies of the order of 20 megacycles or higher.

What is claimed is:

1. A transformer comprising an insulating tube, a primary winding and a secondary winding surrounding said tube, said primary winding comprising a first coil and a second coil spaced from said first coil, said coils being serially connected so as to produce opposing fluxes, said secondary winding comprising a third coil and a fourth coil spaced from said third coil, said third and fourth coils being wound in opposite directions around said tube, and means for electrically connecting said third and fourth coils intermediate their ends to provide a desired mutual inductance for said primary and secondary windings.

2. A transformer comprising an insulating tube, a primary winding and a secondary winding surrounding said tube, said primary winding comprising a first solenoidal coil and a second solenoidal coil spaced from said first coil, said coils being serially connected and wound in opposite directions around said tube, said secondary winding surrounding said primary winding and comprising a third coil surrounding said first coil and a fourth coil surrounding said second coil, the adjacent portions of said third and fourth coils comprising spaced substantially parallel conductors, and means for fixing the coupling between said primary and secondary windings as desired, said means comprising a strap extending between the substantially parallel portions and intermediate the ends of said third and fourth coils and connecting said third and fourth coils in series opposition.

3. A transformer comprising an insulating tube, a primary winding and a secondary winding surrounding said tube, said primary winding comprising a first solenoidal coil and a second solenoidal coil spaced from said first coil, said coils being serially connected and wound in opposite directions around said tube, said secondary winding surrounding said primary winding and comprising a third coil surrounding said first coil and a fourth coil surrounding said second coil, the adjacent portions of said third and fourth coils comprising spaced substantially parallel conductors, and a cross-strap affixed intermediate the ends of said coils electrically connecting said portions and lying substantially parallel to the axis of said tube, said cross-strap connecting said third and fourth coils in series opposition.

4. An inductance device comprising an insulating tube, a primary winding and a secondary winding surrounding said tube, said primary winding comprising a first coil and a second coil spaced from said first coil, said coils being serially connected so as to produce opposing fluxes, a pair of non-magnetic cores adjustable longitudinally along the axis of said tube, said secondary winding comprising a third coil surrounding said first coil and a fourth coil surrounding said second coil and spaced from said third coil and lying substantially parallel to it, and a cross-strap for connection as desired intermediate the ends of said third and fourth coils and connecting them in series.

5. A transformer comprising an insulating tube, a primary and a secondary winding surrounding said tube, said primary winding comprising a first coil and a second coil spaced from said first coil, said coils being serially connected so as to produce opposing fluxes, said secondary winding comprising a third coil and a fourth coil spaced from said third coil, said third and fourth coils being wound in opposite directions around said tube, means for adjusting the inductance of the primary winding, and means for fixing the coupling between the primary and secondary windings as desired to provide a desired mutual inductance.
